DESIGN FOR A PHOTOGRAPHIC ENLARGER

Keith N. Swanson, Hollywood, Calif.

Application October 29, 1945, Serial No. 123,312

Term of patent 14 years

(Cl. D61—1)

To all whom it may concern:

Be it known that I, Keith N. Swanson, a citizen of the United States, residing in the city of Hollywood, in the county of Los Angeles and State of California, have invented a new, original, and ornamental Design for a Photographic Enlarger, of which the following is a specification, reference being had to the accompanying drawing, forming part thereof.

The figure is a perspective view of a photographic enlarger showing my invention.

I claim:

The ornamental design for a photographic enlarger, substantially as shown.

KEITH N. SWANSON.
